CARBURETOR HAVING AN IDLE GOVERNOR
Niels J. Beck, Miraleste, Calif., assignor to McCulloch
Corporation, Los Angeles, Calif., a corporation of
Wisconsin

Filed Feb. 15, 1965, Ser. No. 433,261
4 Claims. (Cl. 261—41)

This invention relates generally to governors for internal combustion engines, and relates more particularly to governors of the suction type.

While the invention has particular utility in connection with internal combustion engines, and is shown and described in such connection, it is to be understood that its utility is not confined thereto.

The problem of providing a suitable and effective governor for internal combustion engines involves certain difficulties. For example, where the suction or velocity type of governor is used in addition to the usual throttle valve of the engine, difficulty in starting the engine may be encountered due to the fact that the throttle valve is in the substantially closed or idle position, even though the governor valve is open.

It is therefore an object of the invention to solve the problem and overcome the difficulties involved therein.

It is another object of the invention to provide an arrangement wherein the throttle valve of the carburetor also functions as the governor valve.

It is still another object of the invention to provide mechanism of this character with which starting of the engine is facilitated and rendered easier than heretofore.

It is another object of the invention to provide mechanism of this character that is extremely simple in construction and operation.

It is a still further object of the invention to provide mechanism of this character having simple adjustment means whereby any desired idle speed may be provided.

It is another object of the invention to provide mechanism of this character that is relatively inexpensive to manufacture.

The characteristics and advantages of the invention are further sufficiently referred to in connection with the following detailed description of the accompanying drawings, which represent one embodiment. After considering this example, skilled persons will understand that many variations may be made without departing from the principles disclosed, and I contemplate the employment of any structures, arrangements, or modes of operation that are properly within the scope of the appended claims.

Referring to the drawings, which are for illustrative purposes only:

FIG. 1 is a sectional view of a portion of an internal combustion engine provided with a carburetor embodying the present invention;

FIG. 2 is a perspective view of a carburetor embodying the present invention, portions of the carburetor being broken away to show the interior construction;

FIG. 3 is a schematic longitudinal sectional view of a carburetor embodying the present invention, as viewed from the side opposite that shown in FIG. 1, with the butterfly throttle and governor valve in the closed position;

FIG. 4 is a similar view showing the throttle, governor valve, in an open position;

FIG. 5 is a side view of the carburetor with the throttle in a partly open position;

FIG. 6 is a similar view with the throttle in the idle position with the engine in operation; and

FIG. 7 is a sectional view similar to FIG. 3 but showing an alternative arrangement.

Referring more particularly to FIG. 1, there is shown a portion of an internal combustion engine, indicated

2

generally at 10, of the two-cycle type. This engine includes a cylinder 11 having a cylinder lining 12 secured therein in the usual well known manner. A portion of the crankcase, indicated at 14, has a crankshaft 15 of the usual well known character connected to a piston 16 by the usual connecting rod 17. The piston 16 is operably disposed within the cylinder lining 12 which may be considered the actual cylinder. The crankshaft has the usual counterweight 18.

An intake manifold 20 is secured to the engine in any well known manner, such as by screws, not shown. Between the manifold 20 and the adjacent portion of the engine is a gasket 21 and a reed valve 22 of well known type. Since the reed valve construction is of known character, it is not believed to require further description. Suffice it to say that the reed valve opens when there is suction in the crankcase to permit the inflow into the crankcase of the fuel mixture. In the engine shown there is a chamber 23 in which the reed valve is located and said chamber communicates with the crankcase interior 14. Chamber 23 also communicates with the interior of the cylinder through a port 24 located so as to be uncovered when the piston is at its inward limit of movement. Opposite the port 24 there is a similar port 25 which is connected with the interior of the crankcase by a passage 26. Port 25 is located so as to also be uncovered by the piston when the piston has approached its inward limit of movement. At the outer end of the cylinder there is a combustion chamber 28 and the head of the cylinder and sides are cooled by fins 29 of the usual character for an air-cooled engine.

Intake manifold 20 has an inlet port 30 at one side and a carburetor, indicated generally at 32, is attached thereto in the usual manner with screws, not shown, received in openings 33 of an attachment flange 34, the mixture outlet 36 of the carburetor discharging into the inlet port 30 of said intake manifold 20.

The carburetor has the usual induction passage with an air inlet portion 37, large and small venturies 38 and 39, respectively, in which the fuel and air is mixed, and the above referred to mixture outlet portion 36.

A disc-type of throttle valve 40 is mounted on a throttle shaft 41 which extends through the induction passage and is rotatably mounted in suitable bosses 42 and 43 at opposite sides of the induction passage. The throttle shaft 41 is above the axial center line of the induction passage and the throttle valve disc or butterfly 40 is mounted in offset relation on the throttle shaft in an unbalanced manner with the greater percentage of its area located below the throttle shaft.

The carburetor is provided with a fuel chamber 46 which is supplied with fuel through a fuel passage 47 controlled by a needle valve 48, the latter being controlled in the usual manner by a diaphragm mechanism 50. The main fuel nozzle or jet 51 is located to discharge into the small venturi 39 and a fuel mixture is discharged from said venturi into the main or large venturi 38. The main fuel nozzle or jet 51 is supplied with fuel through a passage 52 from the fuel chamber 46 into a chamber 53, through a disc 54 having an opening 54a therein, there being a check valve member or ball 54b permitting fuel flow through said opening 54a into the chamber 55 with which the main fuel nozzle or jet 51 is directly connected, reverse flow through opening 54a being prevented by said ball 54b. A needle valve 56 provides means for adjusting the amount of fuel supplied to the main fuel nozzle or jet 51.

The carburetor is also provided with an idling system which includes idle jets 60 and 61 which discharge into the induction passage at the lower end of the large venturi 38, said idle jets being longitudinally spaced apart relative to the induction passage. Fuel is supplied from

the fuel chamber 46 to said idle jets by way of a fuel passage 62 which is connected with a chamber 63 having a direct connection with the idle jets. A needle valve 64 is provided to regulate the supply of fuel from the fuel chamber 46 to the chamber 63 and hence the idle jets.

When the throttle valve is in the closed or the idling position the idle jets 60 and 61 are at opposite sides of the lower end of said throttle valve and supply idling fuel to the induction passage in the usual well known manner. When the throttle valve is moved to an open position the lower edge thereof passes the idle jet 60 so that both idle jets are downstream of said throttle valve and the control of the fuel and fuel mixture in the carburetor is effected in the usual well known manner and further description hereof is believed to be unnecessary.

A coil spring 70 is disposed on one end of the throttle shaft and one end of said spring is fixed or fastened to a screw 71, screwed into the boss 42 of the carburetor.

Attached to the same end of the throttle valve is a disc 73 having a plurality of peripheral notches 74. Spring 70 has a hook 75 at its free end and said hook is disposed in one of the notches 74, the tension of said spring being adjusted by relocating the spring end 75 in respective notches 74. The disc 73 is also provided with a radial arm 76 which is engaged by the inner end 77 of an idle speed adjustment screw 78 which is threadably disposed in a tapped opening, not shown, provided thereon or in a part 79 of the carburetor body. The usual spring 0 is provided on the adjustment screw to retain same in adjusted positions.

The disc 73 is also provided with a radial arm 81 which provides a lever spaced circumferentially from the arm 6. A throttle rod 82 is slidably disposed in a boss 83 formed in the carburetor body and said rod 82 is connected to the usual throttle control mechanism. The end of rod 82 adjacent the disc 73 has a laterally turned portion 82a which is disposed between the arms 76 and 81.

The arms 76 and 81 are angularly spaced apart a sufficient distance so that there is lost motion between said arms and the laterally turned portion 82a of the throttle rod 82.

The throttle valve 40 is urged in the opening direction by spring 70, the opening of the throttle valve being limited by engagement of the arm 81 with said laterally turned portion 82a of the throttle rod. When the throttle mechanism is in the idle position the throttle valve will be in the partially open position, such as shown in FIGS. 3 and 4, for example.

When the engine is started there is a flow of air through the induction passage and this air flow picks up fuel for the fuel mixture in the usual well known manner. Since the throttle valve is partially open at the time the engine is started, adequate fuel will be supplied to provide a quick start. As soon as the engine starts the air flow through the induction passage increases and this flow tends to close the throttle valve since the greater area of this valve is located at the upstream side of the throttle valve when said valve is open. The force of the spring 70 tends to balance the force of air flow effective on the throttle valve, urging same in the closing direction and by adjusting the spring force the force of the air flow and spring will be brought to a balance at any desired idle speed. Thus the idle speed will be governed by the throttle valve of the carburetor.

When it is desired to accelerate the engine the accelerator mechanism thereof is actuated and thereby causes the rod 82 to move in a valve-opening direction. Because of the spring 70 the arm 81 will follow the laterally turned portion 82a of the rod 82, so that the throttle valve will open in accordance with the opening movement of the rod 82.

Should the spring 70 be arranged so as not to fully open the throttle valve as the throttle rod 82 moves in the opening direction, the laterally turned end portion 82a of said rod 82 will engage the arm 76 and positively move

the throttle valve further open. Closing movement of the throttle rod 82 will cause the portion 82a thereof to engage the arm 81 and positively move the throttle in the closing direction. Air flow on the larger area of the throttle valve will also tend to move same in the closing direction.

In the arrangement shown in FIG. 7 there is no small venturi within the induction passage. Otherwise the mechanism is the same as that shown in the other figures.

The invention and its attendant advantages will be understood from the foregoing description and it will be apparent that various changes may be made in the form, construction and arrangement of the parts of the invention without departing from the spirit and scope thereof or sacrificing its material advantages, the arrangements hereinbefore described being merely for purposes of illustration.

I claim:

1. A carburetor for an internal combustion engine, comprising:
  - (A) a carburetor body having an induction passage therethrough, said induction passage having an air inlet and an air-fuel mixture outlet;
  - (B) venturi means in said induction passage;
  - (C) a rotatable throttle shaft extending through said induction passage downstream of said venturi means;
  - (D) a throttle valve disc in said induction passage, said disc being attached in offset relation to said throttle shaft with the greater area of said valve extending upstream in the induction passage when said valve is in an open position;
  - (E) a spring anchor disc secured to said throttle shaft exteriorly of said carburetor body, said anchor disc having a plurality of peripheral notches therein,
    - (a) an idle adjustment arm on said disc, said arm extending outwardly thereof,
    - (b) and a lever extending outwardly of said disc in circumferentially spaced relationship to said arm;
  - (F) a coil spring on said throttle shaft, said spring having one end fixed and having a hook at the other end hooked in one of the notches of said spring anchor disc, said spring urging said shaft in a valve opening direction;
  - (G) an idle adjustment screw cooperable with the idle adjustment arm of the disc for limiting closing movement of the throttle valve;
  - (H) accelerator means including a part disposed between said arm and said lever of said disc, there being a limited amount of lost motion between said part of the accelerator means and the arm and lever of said disc; and
  - (I) means defining a fuel system for the engine, said fuel system including
    - (a) a main fuel jet discharging into said venturi means,
    - (b) and a pair of idle jets disposed downstream of said main fuel jet and located at opposite sides of the throttle valve when the latter is in the closed position.
2. A carburetor for an internal combustion engine, comprising:
  - (A) a carburetor body having an induction passage therethrough, said induction passage having an air inlet and an air-fuel mixture outlet;
  - (B) large and small venturi means in said induction passage;
  - (C) a rotatable throttle shaft extending through said induction passage downstream of said venturi means;
  - (D) a throttle valve disc in said induction passage, said disc being attached in offset relation to said throttle shaft with the greater area of said valve extending upstream in the induction passage when said valve is in an open position;

- (E) a spring anchor disc secured to said throttle shaft exteriorly of said carburetor body, said anchor disc having a plurality of peripheral notches therein,
    - (a) an idle adjustment arm on said disc, said arm extending outwardly thereof,
    - (b) and a lever extending outwardly of said disc in circumferentially spaced relationship to said arm;
  - (F) a coil spring on said throttle shaft, said spring having one end fixed and having a hook at the other end hooked in one of the notches of said spring anchor disc, said spring urging said shaft in a valve opening direction;
  - (G) an idle adjustment screw cooperable with the idle adjustment arm of the disc for limiting closing movement of the throttle valve;
  - (H) accelerator means including a part disposed between said arm and said lever of said disc, there being a limited amount of lost motion between said part of the accelerator means and the arm and lever of said disc; and
  - (I) means defining a fuel system for the engine, said fuel system including
    - (a) a main fuel jet discharging into said small venturi means,
    - (b) and a pair of idle jets disposed downstream of said main fuel jet and located at opposite sides of the throttle valve when the latter is in the closed position.
3. A carburetor for an internal combustion engine, comprising:
- (A) a carburetor body having an induction passage therethrough;
  - (B) a rotatable throttle shaft extending through said induction passage;
  - (C) an offset throttle valve disc in said induction passage carried by said shaft and having the greater area of said valve extending upstream in the induction passage, when said valve is in an open position;

- (D) a disc member secured to said throttle shaft exteriorly of said carburetor body, said disc having,
  - (a) a radially extending idle adjustment arm,
  - (b) and a radially extending lever in angularly spaced relationship to said arm;
- (E) a spring for urging said shaft in a valve opening direction, said spring having one end fixed and its other end variably connectable with said disc to change the effective spring force;
- (F) an idle adjustment screw cooperable with the idle adjustment arm of the disc for limiting closing movement of the throttle valve;
- (G) accelerator means including a movably adjustable part disposed in the angular space between said arm and said lever; and
- (H) main and idling fuel jets for discharging fuel into said induction passage.

4. A carburetor according to claim 3, wherein the movable part of the accelerator means is in the paths of movement of said arm and said lever, said part providing an adjustable stop for said lever and being movable into engagement with said arm to move the throttle valve in an opening direction.
